UNITED STATES PATENT OFFICE.

CLAUD WISEMAN, JOSEPH J. MCKINNEY, AND JOSEPH A. WISEMAN, OF MILWAUKIE, OREGON.

WRENCH.

1,166,295.

Specification of Letters Patent. Patented Dec. 28, 1915.

Application filed February 20, 1915. Serial No. 9,761.

To all whom it may concern:

Be it known that we, CLAUD WISEMAN, JOSEPH J. MCKINNEY, and JOSEPH A. WISEMAN, citizens of the United States, residing 5 at Milwaukie, in the county of Clackamas and State of Oregon, have invented new and useful Improvements in Wrenches, of which the following is a specification.

The present invention relates to improvements in quick acting wrenches.

In carrying out our invention we propose to construct a wrench which may be adjusted to nuts, pipes or other work within a wide range of sizes which in operation may 15 be easily manipulated to engage with or to be withdrawn from the work, so as to tighten or loosen the same and also whereby the jaws of the wrench may obtain fresh holds in an expeditious manner.

20 We also aim to construct a wrench wherein both of the jaws will be simultaneously moved toward the object to be engaged.

It is a still further object of the invention to construct a wrench which shall embody 25 two jaws, each of the said jaws resting upon the other to provide bearings therefor, a carriage or casing being arranged to receive the shanks of the said jaws, the said carriage having pivoted therein a handle having an 30 annular end provided with teeth which are adapted to engage with teeth provided upon the shanks of the jaws, and the carriage being so constructed as to limit the movement of the jaws either in an open or 35 closed position.

With the above and other objects in view, the improvement resides in the construction, combination and arrangement of parts set forth in the following specification and 40 falling within the scope of the appended claim.

In the drawings: Figure 1 is a side elevation of a wrench constructed in accordance with the present invention and showing the 45 jaws of the same in their open position, Fig. 2 is a similar view showing the jaws closed, Fig. 3 is a transverse sectional view approximately on the line 3—3 of Fig. 2, Fig. 4 is a longitudinal sectional view approximately 50 on the line 4—4 of Fig. 2, Fig. 5 is a side elevation illustrating one of the side plates of the carriage removed and showing the manner in which one of the jaws is adjusted with relation to the other jaw so as to

lengthen the range of stroke between the 55 said jaws, Fig. 6 is a perspective view of one of the members comprising the carriage or casing, and Fig. 7 is a perspective view of one of the jaws.

Referring now to the drawings in detail, 60 the numeral 1 designates a wrench constructed in accordance with the present invention. The wrench includes two jaws which we will term outer and inner jaws, the said outer jaw being indicated by the 65 numeral 2 and the inner jaw being indicated by the numeral 3. Each of the jaws is provided with an angular shank 4, the said shanks, adjacent the jaws 2 and 3 being centrally reduced to provide each of 70 said shanks upon its opposite sides with transverse shoulders 5 and 5' respectively. The shanks are adapted to have their adjacent edges contact with each other but the 75 ends of the said shanks adjacent the opposite jaws formed thereon have their adjacent faces reduced or cut-away and the members provided by the said cut-away portions are formed with teeth 6 and 6' respectively.

The numeral 7 designates a casing or carriage, the same preferably comprising two similar members, each of which being formed with a central longitudinal recess or channel 8 so arranged that the outer longitudinal edges of the shanks of the 85 wrench will engage therewith, but also whereby the said shanks, when the members comprising the casing are assembled will engage with the opposite faces of the recess or channel, thus insuring a positive longitudinal movement of the jaws of the wrench in a manner which will presently be described. Arranged within the channels 8 of the carriage or casing 7 is the head 9 provided upon one end of a handle 10. The 90 head is formed with a rounded periphery, and the said periphery is provided with teeth 11, the said teeth co-acting with the teeth 6 and 6' of the shanks of the respective jaws 1 and 2. The carriage 7, at its 100 inner end, is cut approximately centrally in a longitudinal direction and transversely from one of its edges, providing a substantially rectangular cut-away portion. The inner walls of the said cut-away portion 105 provide shoulders 12 which are adapted to be contacted by the shoulders 5' of the jaws 3, when the jaws are spread apart, while

the end of the carriage forward of the shoulders 12 provides contact members with which the shoulders 5 of the jaw member 2 abut when the handle actuates the jaws to bring the same toward each other and when an obstacle is not engaged between the jaws.

It will be noted, from the above description, that the shoulders are normally adapted to contact with the shoulders provided by the end of the carriage to limit the movement of the jaws in both an inward and an outward direction, but it will be noted by reference to Fig. 5 of the drawings that either or both of said jaws may be adjusted within the carriage to lengthen the space between the jaws, and thus readily adjust the jaws to compensate for their engagement with the articles of varying sizes. It is to be further understood that the carriage or casing is separable, the same being preferably secured by means of screws or the like, so that by removing one of the sections of said carriage or casing, the adjustment of the jaws may be readily and quickly regulated.

From the above description, taken in connection with the accompanying drawings, the simplicity of the device, as well as the advantages thereof will, it is thought, be perfectly apparent to those skilled in the

art to which such invention appertains without further detailed description.

Having thus described the invention, what we claim is:

In a wrench of the class described, two jaws having angular shanks, comprising reduced members projecting from the jaws and forming shoulders upon each of the sides of the jaws, said shanks having their adjacent edges opposite their jaws reduced and provided with teeth, a carriage including a hollow member for receiving the shanks, said hollow member having its outer edge formed with a reduced portion providing a stop for the shoulders of one of the jaws and the end of said carriage formed with the reduced portion providing a stop for the shoulders of the second jaw, a handle having a peripheral head received within the carriage and pivotally secured thereto and said head being provided with teeth which co-act with the teeth of the shanks.

In testimony whereof we affix our signatures in presence of two witnesses.

CLAUD WISEMAN.
JOSEPH J. McKINNEY.
JOSEPH A. WISEMAN.
